(57) **CLAIM**

The ornamental design for a battery booster pack, as shown and described.

DESCRIPTION

FIG. 1 is a front isometric view of a first embodiment of a battery booster pack in accordance with the present invention.

FIG. 2 is a back isometric view of a first embodiment of a battery booster pack in accordance with the present invention.

FIG. 3 is a front elevation view of the battery booster pack illustrated in FIGS. 1 and 2.

FIG. 4 is a rear elevation view of the battery booster pack illustrated in FIGS. 1 and 2.

FIG. 5 is a left side elevation view of the battery booster pack illustrated in FIGS. 1 and 2.

FIG. 6 is a right side elevation view of the battery booster pack illustrated in FIGS. 1 and 2; and,

FIG. 7 is a top plan view of the battery booster pack illustrated in FIGS. 1 and 2.

The broken lines shown in the drawings are included for the purpose of illustrating environmental structure and form no part of the claimed design.

1 Claim, 4 Drawing Sheets
